UNITED STATES PATENT OFFICE

2,063,253

VACUUM CLEANING DEVICE

Carl Kühnel, Berlin-Charlottenburg, Germany,
assignor to Siemens-Schuckertwerke Aktiengesellschaft, Berlin-Siemensstadt, Germany, a corporation of Germany

Application November 24, 1934, Serial No. 754,583
In Germany November 25, 1933

1 Claim. (Cl. 15—158)

My invention relates to a vacuum cleaning device and more particularly to a rotary brush for floor polishing, cleaning and the like of the type disclosed in my U. S. Patent No. 1,984,191, dated December 11, 1934, and of which the present application is a division with respect to Figs. 4 and 5 originally disclosed in the application for said patent.

Suction cleaner nozzles in which a rotatably mounted annular brush is rotated by a vacuum-operated blade wheel are well known. In such nozzles the blade wheel and the brush are separately secured to the shaft carrying the same, the blade wheel being arranged in a particular casing. Furthermore, special air channels are disposed in the walls of the nozzle which direct the current of air through the blade wheel. In such an arrangement a considerable loss of power is caused due to the fact that the air must follow a tortuous path on passing through the suction nozzle so that the residual power hardly suffices to drive the blade wheel. Besides, the dust easily adheres to the surfaces of the numerous corners in the channels and may cause a clogging of the latter.

The object of my invention is to provide an economical vacuum-operated floor polishing brush so simple and compact in design as to ensure a reliable operation thereof and whereby the suction effect of the cleaner is substantially utilized to the full extent for an effective polishing of floors.

According to the present invention the bristles of the brush in contradistinction to the hitherto employed rotary brushes are immediately secured to the lower blade edges of the blade wheel. By omitting the wall between the brush and the blade wheel on which the air impinges in the axial direction the great advantage is obtained in that the suction air may freely flow through the suction nozzle in a substantially straight path. In such a device the greatest portion of power of the air drawn in is utilized to rotate the brush se-

cured to the blade wheel. Such a rotary brush may be, consequently, also employed for vacuum cleaners having a small suction effect.

Figs. 1 and 2 of the accompanying drawing illustrate an embodiment of my invention in a diagrammatic form.

Referring to Figs. 1 and 2, 1 denotes the casing in the shape of an inverted cup forming a vacuum cleaner nozzle having a neck 2 for fastening a flexible tube. In the central portion of the casing 1 a shaft 4 is rotatably mounted on a transverse support 3, the blade wheel 5 being firmly secured to the shaft 4. The rotation of the blade wheel is caused by the current of air passing through the nozzle in the direction of the arrow 15. Rows 6 of brush bristles are arranged on the lower edges of the blades 5 to form radiating series, the bristles extending parallel to the shaft 4. By the rapid rotation of the blade wheel 5 the brush is caused to rotate, so that the surface to be treated is polished in a most effective manner. The whirl of dust caused by the rotation of the brush is drawn through the neck 2 into the dust container of the vacuum cleaner. This device has, consequently, the advantage of being very 20 efficient, economical and simple in construction, light in weight and easy to manipulate. Further, in such a device an electric motor with a particular lead is dispensed with.

I claim as my invention:

A floor finishing device, comprising an inverted cup-shaped casing, a tubular extension on said casing adapted to be connected to a suction device, a transverse support in said casing, a fan blade wheel closing the lower portion of said casing and being journaled in said support and having radially extending rows of brush bristles, each row being fixed to the lower edge of one of the fan blades, to form a brush with bristles arranged in radiating series and rotated by the blade wheel 40 when the latter rotates due to the air drawn by the suction device through the casing.

CARL KÜHNEL.
